V. SZAMIER.
FLUID BURNING LAMP.
APPLICATION FILED MAY 28, 1914.

1,198,877.

Patented Sept. 19, 1916.

UNITED STATES PATENT OFFICE.

VINCENTE SZAMIER, OF TERRYVILLE, CONNECTICUT.

FLUID-BURNING LAMP.

1,198,877.

Specification of Letters Patent. Patented Sept. 19, 1916.

Application filed May 28, 1914. Serial No. 841,500.

To all whom it may concern:

Be it known that I, VINCENTE SZAMIER, a citizen of the United States, and a resident of Terryville, in the county of Litchfield and State of Connecticut, have invented 5 certain new and useful Improvements in Fluid-Burning Lamps, which improvements are fully set forth in the following specification.

10. This invention relates to improvements in lamps, and more particularly to lamps of the fluid-burning type and each of which is capable, upon being upset, of extinguishing its own flame; and its object is to provide 15 a lamp, lantern, or the like, of the character above indicated, which shall be simple and comparatively inexpensive as regards its construction; durable, efficient and reliable in practical service; which shall embody 20 features of construction whereby is insured, upon the same being upset, the extinction, automatically, of the flame thereof; and which shall possess certain well-defined advantages over prior analogous constructions. 25 The invention consists in the combinations, details and parts whereby, together with the novel disposition and relative arrangement of said parts, the attainment of the foregoing object is rendered practicable, 30 all of which will be hereinafter more specifically referred to and set forth in the appended claims.

The invention is clearly illustrated in the accompanying drawing, wherein—

35 Figure 1 is a fragmentary side elevation, partly in section, of a lamp embodying my said improvements. Fig. 2 is a fragmentary plan view of same, the cover for the trip-mechanism housing being removed. Fig. 3 40 is a view showing in side elevation and detached the wick-casing, certain minor parts immediately coöperating therewith being shown in vertical section. Fig. 4 is a view showing in perspective and detached the 45 trip-mechanism which I purpose making use of, together with certain parts provided for coöperation therewith, the scale being somewhat enlarged. Fig. 5 is a bottom plan view of the trip-mechanism housing. Fig. 50 6 is a view showing in perspective and detached the operating, gravity lever made use of.

Having reference to the accompanying drawing, wherein similar reference-characters denote like parts throughout the several views, I, in carrying out my invention, make

use of a fount 2, as of a lamp, lantern, or the like, the same being adapted to contain a combustible fluid, as kerosene, and being provided with a burner 2', in the usual manner, said burner being provided with the usual upstanding wick-casing 2'', upwardly and downwardly on which rides a flame-extinguisher. As here shown, said flame-extinguisher comprises a flattened sleeve 3, 60 freely surrounding the casing 2'', having a downwardly extending arm 3' and provided with an upwardly extending flap 3'', the latter having a rocking action, as at the opposite points 4, 4' and being elastically controlled, as through the medium of a leaf-spring 4'', attached to the sleeve 3 by means of rivets 5, or other suitable fasteners.

The spring 4'' tends at all times to rock and cause the flap 3'' to span and close the 75 sleeve 3, said flap assuming such sleeve-closing position under each due upward thrust of said sleeve and receding therefrom under each downward movement of said sleeve, all as will be readily understood, since the 80 construction thus far described is old and well known in the art.

5' denotes a main lever which extends radially through the wall of the burner 2', by way of an opening 6 formed therein, and 85 operates on a pivot 5'', the exposed portion of said lever affording a finger-piece 6' and a stem 6'' depending rigidly therefrom, while the inner or concealed portion thereof extends to and suitably engages the arm 3', 90 preferably by freely entering an eye 7, (Fig. 3), formed in said arm.

An elastic controller, as the extensible spiral spring 7', is interposed between the lever 5', intermediate of its fulcrum 5'' and the 95 arm 3', and any suitable fixed part thereunder, as the base 7'' of the burner 2', the tendency of said controller being, at all times, to thrust upwardly that portion of the lever 5' lying thereover, thereby causing, 100 through the medium of the arm 3', a like upward movement on the part of the sleeve 3, along the wick-casing 2'', and sufficient to bring the flap 3'' somewhat upwardly beyond the top edge of the adjacent wall of 105 the wick-casing aforesaid, thereby permitting said flap to duly rock, under the impulse of spring 4'', into the position the same assumes, (Fig. 3) for closing the top 110 of the sleeve aforesaid. It will be understood that when the flap 3'' occupies its last-named position, air-circulation proper for

the maintenance of the flame, as customarily induced at the top of the wick-casing 2'', is effectively checked, with the result that the flame aforesaid is accordingly extinguished.

5 The stem 6'' supports at its lower end a vertically swinging clevis 8', which in turn supports a horizontally swinging tongue 8'', the latter affording opposite detent-shoulders 9, 9', which permit the same to be temporarily grasped by opposite jaws 9'', 9''', working, respectively on pivots 10, 10', jointly controlled by a bowed, leaf-spring 10'', and all supported by a platform 11, 10 riveted, or otherwise attached, to the burner 2', exteriorly thereof, and as clearly shown in the drawing.

10 The springs 10'' tends at all times to elastically keep the jaws 9'', 9''', closed, the 20 same being spread apart by the tongue 8'', and exerting thereon, in co-operation with the detent-shoulders 9, 9', thereof, and only upon lever 5' being retracted against the tendency of its controller 7', a temporary 25 holding grasp, as will be readily understood, said tongue being freed from this grasp, to accordingly release the lever 5' for co-operation with the sleeve 3, upon said jaws being duly spread apart, or either thereof moved 30 against the tendency of the spring controlling the same.

15 The elastically controlled jaws aforesaid, and parts more or less immediately co-operating therewith, constitute trip-mechanism which I purpose interposing between the lever 5' and a gravity device which I purpose making use of in this instance, which will be hereinafter described, and whereby said jaws, or either thereof, may be 40 duly actuated, automatically, to release the tongue 8'', when held thereby, and upon the lamp, lantern, or the like, to which my present improvement may be applied, being tilted more or less out of its normal upright 45 position, the construction thus far described, save the gravity device aforesaid, being in all essential details and mode of operation, substantially identical with that constituting the subject-matter of my co-pending 50 application serially numbered 831,982.

55 As to the gravity device aforesaid, the same consists of an arm 11', which swings to and fro horizontally on an upstanding pivot 11'', situated between the jaws 9'', 9''', said arm affording a downturned lip 12, which occupies, at all times, a position intermediate of said jaws, and, being positioned duly away from the pivot 11'', is adapted to reversely actuate either thereof, 60 according to the direction in which the arm 11' may automatically move in practice, said arm radiating from the pivot 11'' in any appropriate direction, and having mounted thereon at its free end a weight 12'.

65 For positively locking the operating parts

of my present improved lamp, as against the tendency of the spring 7', I provide the stem 6'' with a notch 12'', and arrange for co-operation with said notch a minor lever 13, said lever working on a pivot 13', and adapted to be swung into and out engagement with the notch aforesaid, thereby locking or liberating, accordingly, the lever 5', together with all parts provided for co-operation therewith.

75 I prefer that the platform 11 be provided with opposite upstanding side-walls 14, 14', connected by an upstanding end-wall 14'', whereby is formed for the trip-mechanism aforesaid a general, open-top housing, the latter being provided, also by preference, with a removable top-plate or cover 15; and in practice, where such cover is employed, the minor lever 13 may be pivotally attached thereto, at the underside thereof, as clearly indicated in the drawing.

80 It will also be noted that, to provide due clearance for the lever 13 and the gravity-arm 11', the side-walls 14, 14' are suitably cut away, as likewise clearly indicated in the 85 drawing.

85 In operation, should my present improved lamp be upset, or even partially tilted out of its normal, upright position, the parts being primarily locked, as through the medium 95 of the jaws aforesaid lockingly engaging the tongue 8'', as hereinbefore explained, and wick 8 maintaining a flame at its top, the arm 11', through the medium of the weight 12' carried thereby, will automatically move 100 in a manner to break, through the medium of its lip 12, the locking engagement of said jaws with said tongue, thereby releasing the latter and so permitting the lever 5' to respond to spring 7', with the result that such 105 upward movement on the part of sleeve 3 is induced as will permit the flap 3'' to undergo proper movement for closing the top of said sleeve, thereby effectually extinguishing the lamp-flame, this all being accomplished automatically and very promptly 110 upon the lamp being upset, or measurably tilted out of its normal upright position.

115 It will be seen that my present fluid-burning lamp is well adapted for the purposes for which it is intended, and further that the same may be modified to some extent, particularly as regards the specific character of the trip-mechanism made use of, the specific character of the gravity-arm availed of, and 120 as regards various minor details of the general construction, without materially departing from the scope of the claims hereto appended.

125 I claim:

1. In a lamp or the like, the combination with a wick-casing having a spring-controlled flame-extinguisher mounted to slide thereon, of a pivotally disposed gravity-arm, 130 freely movable horizontally with respect to

said wick-casing, and trip-mechanism, the latter interposed between said flame-extinguisher and said gravity-arm, adapted to lock the former against the stress of its controlling spring, and, thereafter, to release the same for response to the stress of its controlling spring, under any automatic action on the part of said gravity-arm due to the tilting of said lamp out of its normal, upright position.

2. In a lamp or the like, the combination with a wick-casing having a flame-extinguishing device mounted to slide thereon, of a spring-controlled operating lever, whereby said flame-extinguishing device is duly actuated, a pivotally disposed gravity-arm, freely movable horizontally with respect to said wick-casing, and trip-mechanism, the latter interposed between said operating lever and said gravity-arm, adapted to duly restrain the former against the stress of its controlling spring, and, thereafter, automatically release the same for response to the stress of its controlling spring, under any action on the part of the aforesaid gravity-arm due to the upsetting of said lamp, or the tilting thereof out of its normal, upright position.

3. In a lamp or the like, the combination with a wick-casing having a flame-extinguishing device slidably mounted thereon, of a spring-controlled operating lever whereby said flame-extinguishing device may be actuated, said lever affording a depending part having a tongue pivotally attached thereto at its lower end, a spring-controlled jaw engageable by the tongue aforesaid for restraining said operating lever against the stress of its controlling spring, and a pivotally disposed gravity-arm, the latter freely movable on the pivot which supports it, and when moved by its own gravity, as by the upsetting of said lamp, or tilting thereof measurably out of its normal upright position, adapted to automatically actuate said jaw in a manner to release from engagement therewith, the tongue aforesaid.

4. In a lamp or the like, the combination with a wick-casing having a spring-con-

trolled flame-extinguisher slidably mounted thereon, of a pivotally disposed arm, freely movable on the pivot which supports it and horizontally with respect to said wick-casing, and trip-mechanism, the latter interposed between said flame-extinguisher and said arm, adapted to lock the former against the stress of its controlling spring, and, thereafter, to release the same for response to the stress of its controlling spring, under any action on the part of the arm aforesaid due to the upsetting of said lamp, or the tilting thereof out of its normal, upright position, said arm being provided with a weight at its free end.

5. In a lamp or the like, the combination with a pivotally disposed, spring-controlled operating lever having a stem depending therefrom, of a notched tongue, pivotally attached to said stem at the lower end thereof, and a pivotally disposed, notched jaw, the latter freely movable horizontally with respect to the stem aforesaid, and coöperating with said tongue in a manner to restrain the operating lever aforesaid against the stress of its controlling spring, and, thereafter, to automatically release said lever for response to the stress of its controlling spring, upon said lamp being upset, or tilted out of its normal, upright position.

6. In a lamp or the like, the combination with a wick-casing having a spring-controlled flame-extinguisher slidably mounted thereon, of a part movable automatically under its own gravity and horizontally with respect to said wick-casing, and trip-mechanism, the latter interposed between said flame-extinguisher and said part, adapted to lock the former against the stress of its controlling spring, and, thereafter, to release the same for response to the stress of its controlling spring, under any action of the part aforesaid due to the upsetting of said lamp, or the tilting thereof out of its normal, upright position.

VINCENTE SZAMIER.
